UNITED STATES PATENT OFFICE.

ERASTUS E. PIERCE AND LEWIS W. NEWTON, OF NEW BRIGHTON, PENNSYLVANIA, ASSIGNEES
TO STANDARD HORSE NAIL COMPANY, OF NEW BRIGHTON, PENNSYLVANIA, A CORPOR-
ATION OF PENNSYLVANIA.

NAIL-FINISHING MACHINE.

No. 908,493.

Specification of Letters Patent.

Patented Jan. 5, 1909.

Application filed September 24, 1903. Serial No. 174,496.

To all whom it may concern:

Be it known that we, ERASTUS E. PIERCE and LEWIS W. NEWTON, both citizens of the United States, and residing at New Brighton, 5 in the county of Beaver and State of Pennsylvania, have invented certain new and useful Improvements in Nail-Finishing Machines, of which the following is a specification.

10 In the art of making horse shoe nails judicious cold rolling is very important, but it is capable of being carried to excess. When the nails are rolled from a rectangular rod, it is customary to use a rod having a cross 15 sectional area just a little in excess of the blade of the nail where it joins the head, and upsetting the stock to form the head. If larger stock is used too much cold rolling necessarily follows, reducing the quality of 20 the finished nails, and heads less uniform in size and quality are produced by the cold process than those that are hot forged.

It is our purpose to combine the advantages of the best amount of cold rolling in 25 the blade, with a uniform head in which the stock has not been so overworked as to reduce its ductility and usefulness. To effect these results we construct a machine by means of which the forged blanks having 30 heads in all respects constructively completed, and blades proportioned for the best amount of cold rolling for tensile strength and stiffness, are stamped with the trademark or other design if any is required, 35 rolled, beveled and curved, sheared and re-beveled.

The novel features of this machine will now be fully set forth, reference being had to the accompanying drawings in which:—

40 Figures 1, 2, are front and side elevations of the machine; Fig. 3 is a plan view; Fig. 4 is a cross sectional elevation; Fig. 5 is a side view of the branding and transferring device; Fig. 6 shows some of the parts of Fig. 45 5 in different positions; Fig. 7 is a front view of part of the devices shown in Fig. 5; Fig. 8 is a plan, in cross section, of the magazine tube, showing the detent; Figs. 9 and 10 illustrate details; Fig. 11 is a partial plan 50 view of one set of rolling dies and adjuncts; Fig. 12 is a side elevation of the same; Fig. 13 is an outer end elevation of Fig. 12; Fig. 14 is a section on the line 14—14, Fig. 11; Fig. 15 is a section on the line 15—15, Fig. 55 11, showing the adjusting devices for chang-

ing the position of the centers of the die holders; Fig. 16 is an edge view of one of the roller dies; Fig. 17 is a vertical section of the rebeveler, showing a nail in contact with working parts; Fig. 18 is a plan view of rebeveler and adjuncts; Fig. 19 illustrates the form of the front of the nail before rebeveling; Fig. 20 illustrates a reworked or rebeveled point; Fig. 21 is a side elevation of the beveler-curve; Fig. 22 is a sectional elevation of the shears and punch holder; Fig. 23 is a plan view of both the beveler-curve and shears; Fig. 24 is a side elevation of the same; Fig. 25 is an end or outer elevation of the shears and the beveler-curve; Fig. 26 shows 60 views of the "shears - centering - fingers"; Fig. 27 is a detached view of the shaft carrying the branding device; Fig. 28 is a detached view of another arm of the branding device; Fig. 29 is a plan of the spring retaining hook 65 arms of the transfer device; Fig. 30 is a longitudinal vertical section of the blank holder; Fig. 31 a longitudinal section of the presser bar; Fig. 32 a plan of the turret and operating parts.

In some of the views some of the parts are omitted to more clearly exhibit the remaining parts and the views are drawn to different scales.

The nail blanks, as described, are conducted to the machine one at a time through a magazine tube 51, Figs. 1, 2, 7 and 8, and are each operated on successively until finished. The first operation, while the blank hangs suspended between fixed separated 90 jaws 52, 52 below the tube 51, Figs. 6 and 7, consists in carrying the blank forward by a presser 56 impressing the head against a die or stamp 54, Fig. 5, having a design on its face and by which a trade mark, number, or 95 other imprint is made. The presser then moves back and down and the blank is then carried backward from the jaws 52 by reciprocating fingers 57, 57, by which it is conducted below a blank holder L, having claws 100 between which the head of the blank is passed, and by which it is gripped and the blank is then drawn upward. The holder L is then carried in a circular path one step, and descends to carry the shank of the blank between the first pair of separated roller dies 105 83, 83, (Figs. 3 and 11 to 16). The dies are then brought to bear on the blank which is drawn up as the dies rotate and draw out the stem. On reaching the limit of its upper 110

motion, with the stem above the dies, the holder moves another step carrying the blank above and then down between a second pair of roller dies, which will close upon the blank, 5 which is then again drawn up, and so on in connection with any desired number of dies. As shown there are eight pairs of roller dies, preferably, each carried by a housing F; but the number may be varied. After the drawing operations the blank is carried to a device 10 G, Figs. 1, 3, 21 to 25, termed a "beveler and curver" to be beveled and curved or "set" and thence is presented to a suitable shearer or cutter H and sheared, and is then moved 15 onward another step to a "rebeveler" I when the beveled point is again pressed and condensed so as to solidify it, the arching caused by shearing is removed, the corners squared, and a better finish and a superior 20 quality imparted to the nail. The nail is then ejected into a suitable chute. These operations may be effected by means of devices of different constructions combined in an operative machine so as to secure an automatic feeding, grasping, stamping, drawing, 25 setting, shearing and condensing of the nail, and are all combined and arranged to operate in the machine illustrated, but before describing the manner in which they are supported and operate, we will describe in detail the different individual devices.

The blank feeding devices.—The nail blanks to be finished are fed by any suitable means to a magazine tube 51. The body of this 30 tube is shown as formed of a steel bar, rectangular in cross section and having a longitudinal groove 402 in one face of a size suited to the heads of the nails to be finished. To the grooved face of said bar are secured two 35 steel strips 403, separated sufficiently to provide a sight opening or slot through which the passage of nails down the tube can be observed.

To the lower end of the feed tube are rigidly secured, by means of a screw-bolt 401, 40 two L-shaped pieces 400, the ends of the inwardly projecting portions of which are beveled at their upper faces to correspond to the angle of the lower face of the nail heads and 45 constitute the jaws 52, between which the shank of a nail passing from the feed tube will extend and be supported by engagement of its head with said jaws. For controlling the passage of blanks through the feed tube 50 and to the said jaws 52 the following means are employed. A transverse channel 404 is formed at the lower end of the feed tube in the rear of the face plates or strips 403. This channel extends through the L-shaped 55 pieces 400 and the front face of the main piece or body of the feed tube; and is about two and one-half times as deep as the channel or groove 402 down which the nail blanks pass. A plate 405 is secured to the outer face of the 60 right-hand piece 400, being clamped by the

screw bolt 401. To prevent displacement of the L-shaped pieces 400 when the plate 405 is moved as hereinafter described, said pieces 400 are provided with dowel pins, not shown. In the front edge of the plate 405 is formed a 70 notch, the rear side of which is in alinement with the rear wall of the channel 404. The top of said notch is inclined as shown at 405^a, Fig. 5, and the lower horizontal side thereof is on a higher plane than the bottom of the 75 channel 404. In the channel 404 is arranged an adjusting and holding bar 406, the right-hand end thereof being reduced in thickness and extending outwardly through the afore- 80 said notch in the plate 405 and being engaged by an arm 407 mounted on a shaft 408, Fig. 7. By loosening the bolt 401 slightly, the lower end of the plate 405 can be swung to one side to permit the withdrawal of the bar 406. The top 405^a of the notch in plate 405 is in- 85 clined as shown to allow the plate to swing back for the purpose of removing the bar 406, which could not be done with the plate swinging on the bolt 401 as a pivot if the top of the notch was fitted to the bar 406. 90

A passage or bore extends throughout the length of the vertical member of each L-shaped piece 400, Fig. 10, said passages being reduced in diameter for a short distance near their upper ends. In said passages are arranged plungers 409 the lower ends of which rest on the bar 406. The upper portions of said plungers are reduced in size forming stems around which are arranged coiled springs 308, said springs abut- 100 ting at their ends against the internal shoulders at the upper ends of the wider portions of said passages and against the shoulders formed on the plungers. Collars 410 secured to the upper ends of said plungers, which 105 extend above the pieces 400, limit the downward motion of the plungers.

A groove 411 (Fig. 10) is formed in the front face of the slide bar 406 and, when the bar is moved to the right so as to bring a 110 shoulder 412 thereon against the plate 405, alines with and forms a continuation of the groove 402 in the feed tube. A notch 413 is formed in the lower face of the slide bar 406 and extends continuously across said bar. 115 This notch is of greater depth on the left-hand side, looking at the face of the feeding device, than on the right-hand side and is wider at its rear than at its front end. The left-hand wall of said groove 413 extends at 120 substantially right angles to the front face of the slide bar while the right-hand side is inclined as shown, so that the slide bar 406 will complete its travel to the left gradually. It can travel to the left from the position 125 shown in Fig. 10 only so fast as it is allowed to do so by the withdrawal to the rear of the nail head. If the groove 413 was straight through the bar, the bar could not move to the left at all till the nail head was entirely 130

out of the groove and then it would move with a jump and stop with a shock at the end of its movement, owing to the fact that movement is imparted to the bar by spring pressure.

The blanks are severally arrested in the feed tube 51 by a detent 309, Fig. 8, which is secured to a spring 310 and extends through the slot in the feed tube between the strips 10 403. Means are provided for forcing said spring and detent outwardly at intervals to release the blank suspended by the detent. Said spring 310 and detent 309 are supported by a yoke 414 which is clamped to the feed 15 tube by a set screw 450, the head of the screw being forced against the tube as shown. This connection permits adjustment of the yoke and the detent vertically of the feed tube as may be required for nails 20 of different lengths. The free end of the spring 310 bears against the beveled face of a bar 311 formed integral with an arm 416 on the shaft 408, to which shaft the operating arm 407 of the slide bar 406 is connected, as 25 above described.

The operation of the parts above referred to is as follows:—Assuming that the arms 416 and 407, and the bar 406, are in such positions that said slide bar has been moved 30 to the limit of its movement to the right, so as to bring the shoulder 412 thereon against the inner face of stop plate 405. As the machine is set in operation, arms 416 and 407 are moved to the left, causing the slide bar 35 406 to close the passage from the feed tube to the jaws 52 and causing the beveled face of bar 311 to move the free end of spring 310 outwardly, withdrawing the detent 309 from the feed tube and allowing the blanks in the 40 tube to fall until the point of the lower one rests on the slide 406. After a short pause the above described motions are reversed, the detent 309 is moved into the feed tube and comes into contact with the second 45 blank therein, the vertical groove 411 in the slide being brought into alinement with the passage in the feed tube permitting the lower blank, previously supported by said slide, to fall from said tube between and have its 50 head caught by the jaws 52. The next leftward movement of the arms 416, 407, and slide bar 406 is interrupted by the engagement of the head of the blank then engaged by the jaws 52 with the forward end of the 55 inclined side of slot or groove 413. At this time the nail supported by said jaws is pressed downwardly and against the left-hand jaw 52 by the springs 308 and plungers 409 acting on said bar 406 and by the arm 60 407 which is exerting pressure to the left on said bar 406. The blank is now held firmly against the left-hand jaw 52 and is in the proper position, both laterally and vertically, to be branded or stamped.

65 *The branding and transfer devices.*—A

suitable die 54 is supported in a holder 55 opposite the face of the head of the blank supported as aforesaid by the jaws 52. This die holder is provided with curved slots 360 to receive bolts 300 by which it is adjustably 70 secured, to swing on a curve, to a carrier 301. The blank is forced against the die by a pressure 56 secured in an inclined position in an arm 58 on a rock shaft 304, Figs. 1, 2, 27, and this arm 58 is carried towards the 75 anvil by an arm 60, carried by a sleeve 306^a rocked on the shaft 304. A bolt 305 extends through both arms 58 and 60 and has a nut 306 bearing on a spring 62 which is compressed as the arm 60 is carried forward 80 so as to allow a slight yield if the pressure is too great. The adjustment of the nut also secures an adjustment of the arm 58. The vertical sliding movement of the preser 85 bar 56 on the arm 58 is controlled by a link 67 pivoted to the side of the arm and at its lower end pivoted to a fixed stud 69 so that as the arm 58 swings inward, the link will assume an inclined position and draw the presser bar downward to avoid 90 contact with the claws of the blank holders L. The presser bar is recessed to receive a spring 70, Fig. 31, which prevents any tendency to cramping on the link joints or pins when the presser bar 56 is at its lowest point. 95 The reciprocating fingers 57 are secured to a block 64 which is removably bolted to the arm 58 by a bolt 66. As the arm 58 is moved toward the die holder said spring fingers 57 move with the presser bar 56 and 100 the shoulders 312 on said fingers pass the nail blank just in advance of the presser bar coming into contact with the head thereof to force it against the die. The inner surface of the ends of the fingers 57 are beveled 105 as shown at 57^a so that they are easily separated by and enabled to pass on opposite sides of the blank. As soon as the branding is completed the motion of the arm 58 is reversed, the presser moves back and down 110 and the blank is carried by the fingers 57 coöperating with the presser 56 to one of the blank holders L, it being forced to follow the movement of the bar 58 by reason of its two outer corners being engaged by the 115 shoulders 312 of the fingers 57. As the branded blank is thus withdrawn from the die the previously interrupted leftward movement of the slide bar 406 is completed (the fingers 57 withdrawing the blank rear- 120 wardly through the slot 413) and the detent 309 is withdrawn from the feed tube, permitting the second blank to fall until its lower end rests upon said slide bar 406. This cycle of operations is repeated 125 continuously while the machine is in operation.

The shaft 408 by which the slide bar 406 and detent 309 are actuated, as above described, is driven as follows: This shaft, 130 which is arranged in a vertical position is of

square cross section throughout the greater portion of its length, but has two journals formed thereon, the one at the lower end of the shaft having a bearing at 120° in the bed plate 120 and the second journal, near the upper end of the shaft, extending into a bearing which is secured to the feed tube 51. Near its lower end the shaft 408 is provided with an arm 417, preferably formed integral with the shaft and extending at right angles to the direction of the length of arms 407 and 416. Mounted and sliding on the bed-plate 120 below said arm 417 is a block 418, having a pin 418^a extending upwardly therefrom and into a hole 417^a in the arm 417. Through a passage in said block 418 works the sliding bar 419. This bar has a head at one end and a nut at the other and about it are arranged two compression springs S' and S², the one, S', being between the head and the block 418, and the other, S², between the nut and the block. The head of the bar 419 is provided on its sides with grooves into which extend the legs of a forked plate 420 which is bolted to the arm 58 by the screw bolt 420^a. The said grooves or slots in the head of bar 419 are made relatively large to avoid any cramping when the plate 420 and bar 419 change their positions and angles relative to each other, any lost motion of the forked plate in the said slots being of no consequence. It will be seen that the motion of the bar 419 longitudinally and the position of its head laterally are controlled by the plate 420 on the moving arm 58, and that the central portion of the bar is controlled in its position laterally by the block 418.

As the fingers 57, 57, carried by the arm 58, approach the nail as before described, the bar 419, being driven or moved longitudinally in the same direction by the plate 420, carried by the same arm 58, compresses the spring S' against the block 418, and rotates the shaft 408 which is connected as aforesaid with the block. Such rotation of shaft 408 continues until the bar 406 engages and is stopped by the head of the nail as before described, or, if there is no blank hanging in the jaws 52, 52, until the bar 311 comes in contact with a screw or stop projecting from the feed tube 51 and which determines the limit of motion to the left of the arms 416 and 407. Any further motion of the bar 419 toward the block 418 has no other effect than to further compress the spring S'. As the fingers 57, 57 withdraw the branded blank from the jaws 52 to transfer it to one of the blank holders L, the slide bar 406 of the feed devices completes its motion to the left, and the detent 309 is withdrawn from the feed tube to release the blank just above the bar 406 as before described. These motions are completed by the pressure of the spring S' against the block 418, notwithstanding the fact that the bar 419 is receding along with the fingers 57, 57, and arm 58, said spring S' being of such length, strength and elasticity as to accomplish the desired result. The return motion of the block 418, 70 bar 406, etc., is accomplished through the medium of the spring S², as will be readily understood.

The blank holders.—Each blank holder (one of which is shown in detail in Fig. 30) is 75 mounted to slide vertically in a tubular casting 84, Figs. 4 and 5, and consists of a sleeve 59, Fig. 30, a stem 71, having a limited sliding motion in the sleeve, claws 73, 73, carried by the stem, and a spring 72 surrounding the stem in the sleeve and tending to force the sleeve downward. The lower end of the stem is slotted to receive the shanks of the claws which are pivoted together by a pin 313 passing through overlapping ears beneath which extends a pin 82 crossing the slot of the stem and supporting the claws so as to allow a slight vertical movement of the latter, the outer edges of which are beveled so that when the sleeve moves downward 90 the claws will be carried toward each other. The stem has a head 105 provided with a crank pin 74, eccentric to the stem and whereby the stem may be turned sufficiently to present the blank in different positions 95 successively to the different operating devices, and the sleeve is prevented from descending, in case of breaking of the pin 82 or the claws, by a split ring 207 seated in an annular groove 206 near the top of the sleeve, 100 said ring bearing on a shoulder of the stem. The removal of the ring is facilitated by an opening 208 through which a rod may be passed.

On the descent of the sleeve 59 it is arrested by a stop 75, Fig. 5, on the frame, while the stem and other parts descend further, which opens the claws, prior to the head of the blank being carried between them. The stem and claws are now lifted, the claws 110 gripping the head firmly, as the sleeve is pressed down by the spring 72. As the head is introduced between the claws, they are prevented from opening too far by guides, not shown, so arranged as to occupy positions opposite the edges of the claws when the holder is at its lowest point.

The rolling dies.—The dies 83, Figs. 1, 2, 3 and 11 to 16, are in pairs and they may be of any desired number of pairs, eight being 120 shown, each pair carried by a frame or housing F consisting of side pieces 118 and end plate 119. The dies are mounted in holders which have short journals 315, Fig. 12, which turn in eccentric seats of cylindrical bushings 123, Figs. 12 and 15, each having worm teeth engaging right and left worms 124 on shafts 125, by rotating which the bushings are turned to set the dies slightly to or from each other. The shafts 125 carry gears 320, 130

Fig. 13, both engaging a gear 319 which secures simultaneous equal movements of the two shafts of each pair of dies in adjusting the latter.

5 Each die is grooved peripherally, as shown, so as to operate on two faces of the shank placed diagonally between the dies, the broad side of the groove being at an angle of approximately thirty degrees and the 10 narrow side approximately sixty degrees from the axis of the roll. It has been found that this construction results in imparting a more regular shape and better finish to the stems of the nails. The dies are turned by 15 the teeth of rack bars 86, engaging teeth 123^a of the die holders and guided in the frames F. The dies are separated when the holder L carries the stem of a blank downward between them, or are turned downward to such 20 an extent as to leave a free passage between them; but when the holder begins to rise the rack bars 86 begin to descend and turn the dies into engagement with the stem at a point close to the head, and the holder rises at a 25 speed regulated to suit that of the dies which gradually reduce the stem. As the maximum amount of adjustment of the rolling dies will not exceed a distance equal to one-fourth the length of the gear teeth 86, 132^a, 30 the latter will always remain in engagement. This operation is repeated by carrying the blank down and then up between the next pairs of dies, and so on until all have operated on the stem, the swinging of the holder presenting a blank with one corner outward between one pair of dies and then with the other corner outward between the next pair of dies.

The beveler-curve.—After leaving the last 40 pair of dies the blank is presented to the beveler-curve G, Figs. 1, 3, 4, 21 to 25, which swages in the bevel for the point, "sets" the shank, and straightens the head if out of position. The point is swaged by two dies 127, 45 128, Fig. 21, the shank is curved by a die 134 and plunger 133, which springs it against the die, while the head, resting back on the die 134, is held in place by a plunger 139. The dies 127 and 134 are supported in a bracket 50 166, and the die 128 and plungers 133 and 139 are supported on an arm 142 swinging on a pin 143 passing through the bracket. The die 128 is adjusted by a backing screw 130, and the die 127 by an adjusting screw 129 55 having a beveled face v against which the inner end of the die bears, a set screw 131 securing the die in place, while a set screw 132 secures the die 128 after adjustment.

The plungers 133, 139 bear on springs 319, 60 320, which are strong enough to resist ordinary pressures, but permit a slight yield when the pressure is excessive, and nuts 135, 136, limit the inward movements of the plungers upon the arm 142.

An adjustable stirrup 140, Figs. 4 and 21, 65 carries the die 134 and controls the vertical position of the same, the height to which the stirrup or gage is set being regulated by distance pieces 141.

The shears.—The shears H, Figs. 1, 22 to 26, operate upon the end of the nail blank and remove the surplus stock to form the point after beveling. These shears consist of a fixed cutter 160, shaped at the end as shown in Fig. 25, and carried by the bracket 75 166, and shaped to shear with moving cutters 162, Figs. 22, 23 and 24, adjusted to receive between their ends the fixed cutter and carried by an arm 163 swinging on a pivot 165 passing through the bracket. The cutters are suitably clamped in place. As the blank is presented to the punch or cutter 160, and the arm 163 swings upward, two spring supported fingers 164, Fig. 23, with bevel ends which can pass on opposite sides of the 85 cutter 160, bear with a yielding pressure on the opposite side edges of the blank stem and center the same to insure equal shearing at the two sides. The spring support for each finger consists of a flexible arm 500, Figs. 23 90 and 26. The pivot 165 of the arm 163 is so arranged outward beyond the face of the cutter 160 that the cutting ends of the cutters have a motion upward and outward which will detach the part sheared from the face of 95 the cutters, preventing it from adhering and interfering with subsequent operations.

The rebeveler.—The rebeveler I, Figs. 17 to 20, serves to solidify the point, removing the arching caused by shearing, squares the 100 corners and makes the nail a better driver. It further is the means of extracting the nail from the holder L. In this device a slide 190 has separated plates 191, Fig. 18, provided with beveled portions or fingers 194 on 105 which the head of the blank will rest as in Fig. 17, its position in respect to the rebeveling dies being thus defined, its head also entering a notch 193 in a block 196, Fig. 18, between which and the edges of plates 191 110 the shank of the blank extends. The nail cannot now turn out of position as it fits a channel 192 formed between the face of the block 196 and the plates 191, which channel is proportioned to the size of the blank operated on, and properly confines it. The block 196 has a stem sliding in a recess in bracket 320, and pressed inward by a spring 321, while a block 195 also has a stem sliding in the bracket and is pressed inward by a spring 115 322 so as to bear on the shank of the blank near the lower end. In an inclined recess of the bracket 320 slides a spring supported die 197, the end of which is opposite a die or anvil 203 set in the block 190 in position to be back of the extreme end of the blank, the beveled face of which is re-pressed as the blank is carried against the die and against 120 125

the blocks 195, 196 by which the stem is held in proper position while the point is condensed and solidified.

After the blank holder L descends and 5 presents the blank in position opposite the slide 190 the latter, moving outward, (to the left, Fig. 18) contacts with the stem and carries the blank outward from between the claws of the holder, and the blank falls until 10 its head rests on the beveled surfaces or stops 194 of the plates 191. When the slide 190 moves back the head of the nail is pushed off of the fingers 194 by an ejector 199, the same having a cross bar connected to a guide rod 15 attached to the bracket 320 and provided with a stop 202, said ejector being pushed inward by a spring 360, Figs. 17, 18, which causes it to move with the block 190 away from the blank, but before the slide 190 completes 20 its inward motion the cross bar of the ejector strikes the stop 202 and is arrested, while the slide moves inward until the head of the nail is pushed off the fingers 194 by the ejector bar. The released nail falls into a 25 suitable receptacle.

While the above devices may be supported and operated conjointly in different ways, we will now describe the manner in which they are placed in a machine which has 30 proved extremely effective.

A is a frame of the machine supporting the bearings of the main shaft B and of the rock shaft 304 and also supporting the bed plate 120 on which are assembled the frames 35 F of the roller dies and the supports for the magazine tube 51 and the beveler-curve G, shearers H, and rebeveler I. These devices are symmetrically arranged in a circle on the bed plate as shown in Fig. 3.

40 There is any required number of blank holders L depending from a frame D to be described. Said holders slide vertically in casings 84 and are moved in a circle by said casings, which are secured to a turret E, 45 which has a step-by-step rotary motion. The intermittent rotation of the turret is effected by a roll 380, Fig. 32, on a disk carried by a shaft 330, which roll engages lugs 381 projecting downward from the 50 ret. A cam 382 on the said disk operates a lever 384 pivoted at 385 and carries a block 386 which when between two lugs 381 prevents the turret from turning. A spring 387 swings the lever inward. This turret E rotates round a cylinder 88 bolted to or forming part of a cylinder 126 secured to the bed plate 120. The vertical reciprocating movements of the blank holders are imparted from a vertically reciprocating frame D having 55 at the under side an annular channel 110, receiving the caps 105 at the upper ends of the stems 71, which caps therefore travel in the channel as the turret revolves. The caps are held in the channel by rings 103, 60 104, bolted to the under side of the frame D,

and extending beneath said caps, Figs. 4 and 30. The crank pins 74 extend upward from the caps into a groove 102 and travel therein, the different sections of said groove being at different angles as shown by dotted lines, 70 Fig. 3, to move the pins inward and outward and thereby swing the caps and turn the stems 71 to which they are attached and thus properly present the blanks to the different operating devices. The frame D is 75 timed in its movements to work in unison with the operations on the blank, being moved upward by a cam 100 on the shaft B, and lowered by gravity but regulated in its descent by the cam. 80

The frame D is connected to a central spindle 115, fitting a hollow plunger 114 carrying at the lower end an antifriction roller 117 which bears on the cam 100. The plunger slides and is guided in the cylinder 85 88. The frame D is prevented from rotating by a bracket 107 having an opening through which extends an upright 106 on the main frame, Fig. 3. An opening 108 in the frame D is in such position that the 90 holders can be extracted when brought in position below said opening, the springs 72 holding the stems in place in the sleeves 59 supported by the turret E as the holders pass the opening. The vertical adjustment of the 95 frame D may be effected by a set screw 112 turning in the frame and bearing at the lower end on a disk 113 in the plunger 114.

Upon the lower part of the cylinder 88 and on a central boss 89 at the base of the frame 100 A reciprocates vertically a ram C provided with radiating arms 85 each of which carries a pair of rack-bars 86, 86, coöperating with one pair of roller dies. This ram is reciprocated by cranks 90 on the shaft B, each being 105 connected to the ram by a short pitman 91 receiving studs 92 projecting from the ram. By this arrangement sufficient dwell is secured at the proper intervals to allow for the rotary movement of the turret between the 110 actions of the different devices operating on the blanks. The bracket 166, which carries the parts G and H (see Figs. 23 and 24), is fitted to the main frame so as to be vertically adjustable thereon, according to the lengths 115 of the blanks, which may be presented to the beveling and shearing devices, the adjustment being effected by means of an adjusting screw 171 turning in and extending through a bracket 176 and provided with 120 nuts 177 for binding the screw after adjustment.

The lever 142 of the device G is vibrated from a cam 146 on the main shaft on which bears a lever 145 (Fig. 4 and dotted lines, 125 Fig. 2) socketed to receive the lower rounded end of a pitman 144, the upper rounded end fitting a socket in the lever 142. The lever 145 is extended as shown in Fig. 2 and has at the end another socket to receive the 130

rounded end of a pitman 325, Fig. 1, the upper rounded end of which fits a socket in the end of the lever 163 of the device H. A spring tension rod 326 connects the lever 163 5 and an arm 327 on the frame, and draws down the lever and also holds the pitman in place. A spring, not shown, acts in the same manner on the lever 142 and its pitman.

The sliding motion of the slide 190 of the 10 rebeveler is effected by a cam 198 (Figs. 17 and 18) on the vertical shaft 330, Fig. 1, which is driven by bevel gears 331 from a counter shaft 332 driven by spur gears 333 from the main shaft.

15 Without limiting ourselves to the construction and arrangement of parts shown, we claim as our invention:—

1. In a machine for cold rolling and finishing horse nail blanks, a stamping mechanism 20 provided with a die, means for delivering blanks with the faces of their heads opposite the die, a presser for forcing the heads towards the die, a blank holder provided with claws, means for cold rolling the blanks 25 while held by said holder, and means for transferring each blank from the said die to a position between said claws, substantially as set forth.

2. The combination of the magazine tube, 30 jaws for supporting the blanks below said tube, a die and reciprocating presser also below said tube for embossing the heads of the blanks while hanging from said supports, fingers, and means for operating them 35 to seize the blanks and carry them from between the jaws, substantially as set forth.

3. The combination in a nail finishing machine, of the reciprocating presser, the die carrier 301, the adjustable die holder 55, 40 and means for securing the holder whereby to present the die in different positions on said carrier at different angles to the presser, substantially as set forth.

4. The combination with the die 54, of 45 the presser 56, holder L, fingers 57 for carrying the blank in advance of the presser, means for carrying the presser to and from the die, and for lowering the presser as it recedes from the die and approaches the 50 holder, substantially as set forth.

5. The combination with the die 54, holder L, and means for carrying blanks from the die to the holder, of the lever 58, the presser 56, sliding vertically in the lever, 55 and a link jointed as described to the presser and to a fixed point on the frame whereby the presser is lowered sufficiently to avoid contact with the holder L, substantially as set forth.

60 6. The combination with the fixed die, the reciprocating presser and jaws 52 for supporting a blank, of the fingers 57, arranged to engage the blank in advance of the presser, and means for moving the fingers

back and for withdrawing the presser, substantially as set forth.

7. The combination with means for stamping the heads of blanks, of a holder L provided with claws 73, means for opening and closing said claws to receive and hold the 70 head of the blank, means for carrying the blanks from the stamping means to said claws, and means for cold rolling the blank stems while held by the holder, substantially as set forth.

75 8. In a nail finishing machine, a rotatable part, holders supported thereby for holding and carrying the blanks, pairs of rolls to which the blanks are successively presented, a casing 84 surrounding each holder and in 80 which the holder is vertically movable, said holder having a sleeve 59, stem 71, and pivoted claws at the bottom of said stem, with inclines adapted to engage the end of the sleeve, combined with a spring interposed 85 between the holder and stem and means for turning said stem within the holder upon its axis, means for sliding it longitudinally in the sleeve to cause the jaws to grip the blank, and means for sliding the sleeve in the casing 90 to release the blank, substantially as set forth.

9. The combination with pairs of rolls to which blanks are successively presented, of a support for a series of sliding holders, 95 the casing 84, sleeve 59 sliding in the casing, stem 71 sliding in the sleeve, spring interposed between the casing and stem, claws 73 engaging the end of the sleeve, means for moving the sliding parts vertically, and a 100 stop for arresting the movement of the sleeve while continuing the downward movement of the stem, substantially as set forth.

10. The combination in a holder, of the stem, a sleeve surrounding the stem and 105 movable longitudinally thereof and provided with an annular recess, and snap ring fitting an annular recess in the sleeve above a shoulder upon the stem, substantially as set forth.

11. The combination in a shearing device, of the fixed and movable cutters, a pivoted arm carrying the movable cutters, and spring fingers 164 on opposite sides of said arm, substantially as set forth.

115 12. The combination in a nail finishing machine, of a rebeveler having the spring supported blocks 195, 196 for engaging the stem of a blank, a spring supported rebeveling die 197, a reciprocating slide carrying a 120 die or anvil 203, and fingers 194 and their supports, substantially as set forth.

13. The combination with a rebeveling device, of dies for operating on the blank, a slide with fingers 194 for supporting the head 125 of the blank, and an ejector 199 for discharging the blank from the fingers when the slide moves inward, substantially as set forth.

14. The combination with the devices for operating on the shanks of the blanks arranged in a circle, of a series of sliding blank holders, a turret adapted to impart motion 5 to said series of sliding blank holders, each provided with a stem having a head at its upper end, and a vertically reciprocating frame above the turret having an annular channel to receive the said heads and reciprocate the holders, substantially as set forth. 10
15. The combination with the revolving turret and holders provided with stems having heads and wrist pins mounted eccentric to the stems, of a non-rotating frame 15 having an annular groove, receiving said heads, and a groove with the different parts at angles to each other to receive the wrist pins, substantially as set forth. 20
16. The combination with the bed plate carrying the series of radially arranged roller dies having pinions on their shafts, of a reciprocating ram C provided with radiating arms 85, and racks carried by said arms and engaging the pinions on the roller die shafts, 25 substantially as set forth.
17. The combination with the means for supporting blanks, of a die, a vibrating arm 58 carrying a presser movable toward and from the die, an arm 60 vibrating adjacent to 30 the arm 58, and a spring connection between the two said arms, substantially as set forth. 35
18. In a machine for finishing horse shoe nails, the combination of a plurality of pairs of rolls, each with a tapering triangular recess having one face broader than the other and at an angle of less than 45 degrees to the axis of the roll, a blank holder adapted to present the blank carried thereby to each pair of rolls with the broad faces of its shank at 40 said angle, and means for moving the blank holder from one pair of rolls to another. 45
19. In a machine for finishing horse shoe nails, the combination of a plurality of pairs of rolls, each with a tapering triangular recess having one face broader than the other and at an angle of less than 45 degrees to the axis of the roll, a blank holder adapted to
- present the blank carried thereby to each pair of rolls with its broad faces at said angle, means for moving the holder and blank from one set of rolls to another, and means for swinging the holder to present each blank with one corner outward between one pair of dies and then with the other corner outward between the next pair of dies. 50 55
20. In a machine for finishing horse shoe nails, the combination of a plurality of pairs of rolls with tapering triangular grooves, each having one face broader than the other and at an angle of approximately 30 degrees to the axis of the roll, a plurality of blank holders, each adapted to present the blanks supported thereby to the rolls with its broad faces at said angle, and means for moving the blank holders to present the blank carried by each successively to the series of pairs of rolls. 60 65
21. In a machine for finishing horse shoe nails, the combination of a plurality of pairs of rolls, arranged in a circle, with tapering triangular grooves, each having one face broader than the other and at an angle of approximately 30 degrees to the axis of the roll, a plurality of blank holders mounted to rotate above the circular series of rolls, each holder being adapted to present the blank supported thereby to the adjacent rolls with its broad faces at said angle, means for moving the blank holders to bring each successively into operative position with relation to several pairs of rolls, and means for adjusting each blank holder to reverse the direction of the aforesaid angle between the broad faces of the blank supported thereby and the axes of the rolls after each rolling. 70 75 80 85

In testimony whereof we have signed our names to this specification in the presence of two subscribing witnesses.
